AUTOMATIC DOOR CONTROLLING
MECHANISMWarren Webster and Kenneth E. Berk, Dayton,
Ohio, assignors to The Joyce-Cridland Com-
pany, Dayton, Ohio, a corporation of Ohio

Application April 3, 1947, Serial No. 739,132

13 Claims. (Cl. 254—89)

1

This invention relates to an automatic door controlling mechanism for use with a lifting mechanism of the type in which the load supporting structure moves through a normally closed opening in a floor or the like. The present apparatus is designed primarily for use with a two-post automobile lift and is in the nature of an improvement on the door controlling mechanism shown in the application filed by Harold N. Grushon, July 12, 1946, Serial No. 683,281, and owned by the assignee of this application.

One object of the invention is to provide a door controlling mechanism which is simple in construction; which is highly efficient in operation; which can be produced and installed at relatively low cost; and which will require a relatively small pit under the floor.

A further object of the invention is to provide such a mechanism which is controlled by the lifting mechanism and which, when the lifting mechanism is either raised or lowered, will open the doors, retain the same open until the load supporting structure has passed through the floor opening, and then close the doors.

A further object of the invention is to provide such a mechanism with means to inform the operator at a remote station whether the doors are open or closed.

A further object of the invention is to provide such a mechanism with means to inform said operator when the superstructure is in a predetermined position with relation to the floor, and thus enable the movement of the lift to be stopped and the axle-engaging elements adjusted on the superstructure.

Other objects of the invention may appear as the mechanism is described in detail. In the accompanying drawings,

Fig. 1 is a perspective view of a two-post lift equipped with the invention, showing the same connected with a source of fluid under pressure;

Fig. 2 is a perspective view of a modified form of the source of fluid pressure;

Fig. 3 is a perspective view of the lifting mechanism for the front axle of an automobile, showing the same in partially elevated position, and partly broken away;

Fig. 4 is a sectional view through the floor showing said front lifting mechanism in side elevation and in its lowered position;

Fig. 5 is a perspective view of the lifting mechanism for the rear axle of the automobile, partly broken away, showing the same partially elevated and with the doors in their open positions;

Fig. 6 is a circuit diagram for the signal lights;

and Figs. 7 and 8 are detail views of the cam mechanism showing the cam in different positions.

In these drawings we have illustrated one embodiment of our invention, and have shown the same in connection with a two-post hydraulically-operated automobile lift, but it is to be understood that the mechanism may take various forms and may be associated with lifting mechanism of various kinds, without departing from the spirit of the invention.

The two-post lifting mechanism comprises a front lifting mechanism including a cylinder 10 adapted to be mounted below the floor or pavement on which the automobile rests, and a lifting element or ram 11 mounted in said cylinder and provided at its upper end with a superstructure 12, which extends lengthwise of the front axle of the automobile and is provided with axle engaging parts 13. A rear lifting mechanism also includes a cylinder 14 adapted to be mounted below the floor, and a ram 15 mounted in said cylinder and having secured to its upper end a superstructure comprising a cross head 16 and a pair of parallel rails 17 extending transversely to the rear axle of the automobile, and of such length as to accommodate the lift to automobiles of various lengths, that is, automobiles in which the front and rear axles are spaced different distances one from the other. For this purpose, axle engaging elements 18 are mounted on the respective rails 17 for adjustment lengthwise thereof. The cylinders 10 and 14 are connected by conduits 19 and 20 with a source of propellant fluid, such as oil. As shown in Fig. 1, the conduits are connected through separately operable valves 21 and 22 with an oil tank 23, which in turn is connected by a conduit 24 with a source of air under pressure. This air is admitted to the tank by a manually operated valve 25 to force the oil from the tank through one or both of the conduits 19 and 20, as determined by the positions of the valves 21 and 22. Any suitable source of oil supply may be utilized, and in Fig. 2 there is shown an oil supply tank 26 of the type in which a motor 27 drives a pump within the tank, not shown, to force the oil through the conduits 19 and 20. The motor is controlled by switch mechanism 28 and the pump may be connected with either or both of the conduits by manually operated valves 29 and 30.

The floor is provided with openings through which the superstructure and rams of the respective lifting mechanisms may move. As best shown in Figs. 3 and 4, the opening 31, through which

the front superstructure passes, is of a size and shape to accommodate the front superstructure 12, and is provided with a frame 32 embedded in the concrete of the floor with its upper surface substantially flush with the floor surface. A pit is provided below the floor and, as shown in Fig. 4, is provided with a housing or liner secured to the frame 32 and having upright walls 33 and a bottom wall 34. The bottom wall is reinforced by a base plate 35, which constitutes a support for various parts of the operating mechanism. The cylinder 10 extends through the base plate 35 and the upper end thereof is spaced below the floor level such a distance that when the lifting mechanism is in its lowermost position the superstructure will be entirely below the floor. The opening 31 is provided with a movable closure which, in the present instance, comprises a pair of doors 36, 37, hinged to the respective longitudinal edges of the frame 32 and so arranged that they will be substantially flush with the frame when in their closed positions. Door 36 comprises end portions 36a and 36b, and an intermediate portion 36c, and the door 37 is likewise divided into three portions. The end portions of each door are provided with lugs 38 which extend beneath the respective ends of the intermediate portion 36c of the door and cause that intermediate portion to move upwardly with the end portions but permits the end portions to move downwardly independently of the intermediate portion, for a purpose which will herein-after appear.

The movement of the doors to their open and closed positions is controlled by mechanism mounted in the pit and controlled by the lifting mechanism, the arrangement being such that upon the initial movement of the lift, from either its lowermost position or its uppermost position, the doors will be opened and held open until the superstructure has passed, and will then be moved to their closed positions by the continued movement of the lift. This mechanism may take various forms but in the present construction it involves crank mechanism connected with the respective doors and controlled by a cam, which in turn is controlled by the lift. In the particular arrangement shown, a rock shaft 39 is journaled in bearings 40 mounted on the base plate 35 and provided with a curved portion 41 to permit the shaft to extend about the cylinder 10. Mounted on the respective end portions of the shaft 39 are crank arms 42 which are connected by rods 43 with the respective end portions of the three-part door 37. Other shafts 44 and 45, mounted in bearings 46 and 47, are arranged parallel with and are spaced laterally from the main shaft 39. Crank arms 48 on the respective shafts 44 and 45 are connected by rods 48a with the end portions 36a, 36b, of the door 36. Crank arms 49 secured to the shaft 39 are connected respectively by links 50 with crank arms 51 secured to the respective shafts 44 and 45, the arrangement being such as to cause the several shafts to move simultaneously in the same direction.

Also mounted on the shaft 39 is a cam-engaging member, here shown as a crank arm 52 having secured thereto a roller 53. A vertical plunger 54 secured to the superstructure 12 extends through an opening in the base plate 35 and is movable with the ram 11. Mounted on this plunger is a cam which, in the present instance, comprises an elongate plate 55 having upper and lower edges oppositely inclined at 56 and 57, and

having a vertical surface 58 connecting the inclined surfaces.

The cam 55 is so arranged that when the lifting mechanism moves upwardly from its lowermost position, as shown in Fig. 4, the upper inclined surface 56 of the cam will contact with the cam-engaging member 52 and rock the shafts 39, 44, and 45 in a direction to move the doors to their open positions, it being understood that the three parts of each door move in unison during the opening movement. When the doors have reached their open positions, the vertical cam surface 58 engages the cam-engaging member and retains the doors in that position until the superstructure has passed above the floor. The continued movement of the lifting mechanism brings the lower inclined surface of the cam into contact with the cam-engaging member and the crank mechanism moves in door-closing direction. In the present arrangement, the doors when in their open positions are slightly inclined inwardly and the weight of the doors and of the crank arms causes the doors to move toward their closed positions. However, during this movement, the intermediate parts 36c and 37c of the doors will contact the ram, which will limit their movement toward closed positions but the end portions of the doors will move to their closed positions. Thus, the major portion of the opening is fully closed by the end portions of the doors and that portion of the opening through which the ram and plunger extend is partially closed. When the lift is lowered, the lower cam surface 57 contacts the cam-engaging member 35 on the shaft 39 and opens the doors, which are held open until the superstructure has passed through the opening and are then closed in the manner above described. The intermediate portions of the doors, as well as the end portions 40 thereof, move to fully closed positions, thus completely closing the opening in the floor. The doors 32 are provided with transverse reinforcing ribs 60 the outer ends of which abut against bars or plates 61 which depend from the frame 32. Ordinarily, this arrangement provides a sufficiently strong support for the doors, but if desired they may be further reinforced by a standard or standards 62 mounted on the base plate 35 and of such length that their upper ends will underlie and support the adjacent edges of the doors when the latter are in their horizontal positions. Preferably, the standard 62 is screw-threaded into a socket member 63 secured to the base plate, to permit the standard to be 55 adjusted to accurately position the upper end thereof with relation to the doors.

The opening for the rear lifting mechanism must be of a length sufficient to permit the passage of the rails 18 of the superstructure. To avoid an unnecessarily large opening in the floor, this rear opening is preferably H-shaped, as shown in Fig. 5, and comprises longitudinally extending side openings 64 and 65 which are connected by a transverse opening 66, which is of relatively narrow width and permits the solid floor to extend close to the ram on both the front and rear sides thereof. Each of the longitudinal openings is provided with a single door 67, hinged 70 at its outer edge to a frame 68 which extends about the several parts of the opening. The transverse opening 66 is closed by a pair of transverse doors 69 and 70, each of these doors comprising two parts. In Fig. 5 the two parts of door 69 are shown at 69a and 69b, the part 69a

having a lug 69c rigidly secured thereto and extending beneath the part 69b.

The mechanism for operating the doors for the rear lifting mechanism is preferably similar to the mechanism for operating the doors for the front lifting mechanism, and as here shown it comprises a rock shaft 71 journaled in bearings 72 on the base plate at the bottom of the pit, and is provided with crank arms 73 which are connected by rods 74 with the respective side doors 67. A crank arm 75 on the rock shaft 71 is connected by a rod 76 with the end portion of the transverse door 70, not shown in Fig. 5, and the crank arm 77 carried by a second rock shaft 78 is connected by a rod 79 with the end portion 69a of the transverse door 69. Other crank arms 80 and 81 on the respective crank shafts are connected by a link 82 to cause the two shafts to move in unison. The shaft 71 is operated by a cam 83, similar to cam 55 above described, and carried by a plunger 84 movable with the lift. A cam-engaging member 85 on the shaft 71 cooperates with the cam to cause the doors to be moved to their open positions, and to be retained in those positions until the superstructure has passed through the openings, and then moved to their closed positions, in the same manner as above described.

The adjustment of the axle-engaging elements 18 on the rails 17 is best effected when the rails are at floor level, or slightly above floor level. It is difficult for the operator at the control station to determine the exact position of the rails with relation to the floor because they are obscured both by the automobile itself and by the doors for the respective openings. We have therefore provided a signal, controlled by the lifting mechanism, which will be energized when the rails are in the desired positions and deenergized at all other times. Preferably, the signal is a visual signal and it is here shown as an electric lamp mounted on or adjacent to the oil tank at the control station, as shown at 86 in Fig. 1. This lamp is connected with a source of electrical energy, not shown, by a switch 87 of a known construction mounted on a fixed part adjacent the superstructure of the rear lift, and shown in Fig. 5 as mounted on the rear wall of the transverse opening in the floor. A part 98, carried, in the present instance, by the cross head 16 of the superstructure, is arranged to engage and close this switch when the rails reach the desired position with relation to the floor, and to maintain the switch closed until the rails move beyond that position.

It is also desirable to provide means for indicating to the operator at the control station whether the doors are open or closed, and additional signal means are provided for this purpose. In the arrangement shown, separate electric lamps 89 and 90 are mounted on or adjacent to the oil tank at the control station, these lamps being of a color different from the color of the signal lamp 86. The lamp for the front lift is connected with a source of electric energy by a switch 91, preferably of the push-button type, and so arranged that the button or plunger 92 will be urged toward its circuit closing position but will be moved by the adjacent door to circuit opening position when the door is moved to its closed position. Thus, when the door is open, the circuit of lamp 89 is closed, and when the door is closed, that circuit is opened. The circuit for the lamp 90 for the doors at the rear lift is controlled by a similar switch 93 which, as here

shown, is arranged to be controlled by one of the side doors 67 in the same manner as switch 91 is controlled. Thus, when any door is open or partially open, one or both of the lamps 89 and 90 will be energized, and when all doors are fully closed, both lamps will be deenergized.

While we have shown and described one embodiment of our invention, we wish it to be understood that we do not desire to be limited to the details thereof, as various modifications may occur to a person skilled in the art.

Having now fully described our invention, what we claim as new and desire to secure by Letters Patent is:

- 15 1. In an apparatus for opening and closing a pit for a lifting mechanism, said pit being adapted to receive the load supporting structure of said lifting mechanism when the latter is in its lowermost position, a movable closure for said pit comprising a plurality of doors movable about separate axes, a shaft mounted in the lower portion of said pit, arms secured to said shaft, means connecting said arms with the respective doors, and means controlled by the movement of said load supporting structure in a single direction to move said shaft in a direction to move said doors to open positions, to retain said doors in said open positions until said load supporting structure has moved past the same, and to thereafter move said shaft in door closing direction.
- 20 2. In an apparatus for opening and closing the pit of a lifting mechanism, said pit being adapted to receive the load supporting structure of said lifting mechanism when the latter is in its lowermost position, a closure for said pit including parts supported at opposite sides of said pit for movement about parallel axes, a rock shaft mounted in said pit and extending transversely to the axes of said parts of said closure, arms secured to said shaft, means for operatively connecting said arms with said parts of said closure, and means controlled by the movement of said load supporting structure in a single direction for moving said shaft in a direction to move said closure to its open position and thereafter move said shaft in closure closing direction.
- 25 3. In an apparatus for opening and closing a pit for a lifting mechanism, said pit being adapted to receive the load supporting structure of said lifting mechanism when the latter is in its lowermost position, a closure for said pit including movable parts extending at an angle one to the other, a rock shaft mounted in said pit, a crank arm on said shaft, means for connecting said arm with one part of said closure, a second crank
- 30 40 45 50 55 60 65 70 arm mounted in said pit independently of said shaft, means actuated by said shaft for operating said second arm, means for connecting said second arm with another part of said closure, and means controlled by the movement of said load supporting structure in a single direction to move said shaft in closure opening direction and to then move said shaft in closure closing direction.
- 75 4. In an apparatus for opening and closing the pit of a lifting mechanism, said pit being adapted to receive the load supporting structure of said lifting mechanism when the latter is in its lowermost position, a closure for said pit comprising a plurality of relatively movable parts, a transverse shaft mounted in said pit, means actuated by said shaft to move the several parts of said closure simultaneously in the same direction, and cam means connected with said lifting mechanism for movement thereby to rotate said shaft first in one direction and then in the other di-

rection while said lifting mechanism moves in a single direction.

5. In an apparatus for opening and closing the pit for a lifting mechanism, said pit being adapted to receive the load supporting structure of said lifting mechanism when the latter is in its lowermost position, a movable closure for said pit, crank mechanism mounted in said pit for movement about an axis below the lower limit of movement of said load supporting structure and transverse to the line of movement of the latter, an upright member directly connecting said crank mechanism with a part of said closure, and means controlled by said lifting mechanism for moving said crank mechanism first in one direction and then in the other direction while said load supporting structure moves in a single direction.

6. In an apparatus for opening and closing the pit for a lifting mechanism, said pit being adapted to receive the load supporting structure of said lifting mechanism when the latter is in its lowermost position, a movable closure for said pit, crank mechanism mounted in said pit for movement about an axis below the lower limit of movement of said load supporting structure and transverse to the line of movement of the latter, an upright member directly connecting said crank mechanism with a part of said closure, and a cam member secured to said load supporting structure, extending downwardly beyond the same and having oppositely inclined parts to successively engage said crank mechanism.

7. In an apparatus for opening and closing the pit for a lifting mechanism, said pit being adapted to receive the load supporting structure of said lifting mechanism when the latter is in its lowermost position, a closure for said pit comprising a plurality of parts movable about separate axes, a rock shaft mounted in said pit below the lower limit of movement of said supporting structure, a plurality of crank arms secured to said shaft, upright members for operatively connecting said crank arms with the respective parts of said closure, a cam arm secured to said shaft, and a cam member connected with and extending downwardly from said load supporting structure and having oppositely inclined and vertically spaced cam surfaces to successively engage said cam arms.

8. In an apparatus for opening and closing the pit for a lifting mechanism, said pit being adapted to receive the load supporting structure of said lifting mechanism when the latter is in its lowermost position, a closure for said pit comprising a plurality of separate parts movable about axes extending at an angle one to the other, two rock shafts mounted in said pit, means for connecting said rock shafts one with the other for simultaneous movement in the same direction, crank arms secured to the respective shafts, means for operatively connecting crank arms on the two shafts respectively with parts of said closure which are movable about intersecting axes, a cam arm on one of said shafts, and a cam movable with said lifting mechanism and adapted to engage said cam arm and actuate said shafts.

9. In an apparatus for opening and closing the pit for a lifting mechanism, said pit being adapted to receive the load supporting structure of said lifting mechanism when the latter is in its lowermost position, a closure for said pit comprising two parts, movable respectively about separate axes and movable by gravity from their open positions to their closed positions, a rock

shaft in said pit, crank arms on said shaft, upright members operatively connecting said crank arms with the respective parts of said closure to move the latter simultaneously in the same direction, and means controlled by the movement of said lifting mechanism for actuating said shaft in closure opening direction and to thereafter release said shaft for movement in closure closing direction.

10. In combination with a lifting mechanism of the type comprising a vertically movable ram mounted in a pit below an opening in a floor, and a superstructure carried by said ram and movable into said pit when said ram moves to its lowered position, selfclosing doors pivotally supported at the upper end of said pit for movement to positions substantially flush with said floor to close said opening and to upwardly extending positions to permit the movement of said superstructure through said opening, a rock shaft in the lower portion of said pit extending transversely to said ram, crank arms on said shaft, upright members connecting said crank arms with the respective doors, and means controlled by the movement of said superstructure in either direction toward said door to move said shaft first in door opening direction and to thereafter release the same for movement in door closing direction during the continued movement of said superstructure in one direction.

11. In combination with a lifting mechanism of the type comprising a vertically movable ram mounted in a pit below an opening in a floor, and a superstructure carried by said ram and movable into said pit when said ram moves to its lowered position, selfclosing doors pivotally supported at the upper end of said pit for movement to positions substantially flush with said floor to close said opening and to upwardly extending positions to permit the movement of said superstructure through said opening, a rock shaft in the lower portion of said pit extending transversely to said ram, crank arms on said shaft, upright members connecting said crank arms with the respective doors, a cam arm on said shaft, and an elongate member connected with said superstructure, extending into said pit and having vertically spaced cam surfaces to successively engage said cam arm and move said shaft first in door opening direction and thereafter release the same for movement in door closing direction.

12. In combination with a lifting mechanism of the type comprising a vertically movable ram mounted in a pit below an opening in a floor, and a superstructure carried by said ram and movable into said pit when said ram moves to its lowered position, selfclosing doors pivotally supported at the upper end of said pit for movement about intersecting axes to positions substantially flush with said floor to close said opening and to upwardly extending positions to permit the movement of said superstructure through said opening, crank mechanism in the lower portion of said pit including a cam arm, means for operatively connecting said crank mechanism with each of said doors, and an elongate member connected with said superstructure, extending into said pit and having vertically spaced cam surfaces to successively engage said cam arm when said superstructure approaches the closed doors from above or below and to move said crank mechanism in door opening direction and to thereafter release the same for movement

in door closing direction after said superstructure has passed through said opening.

13. In combination with a lifting mechanism adapted to be mounted below an opening in a floor and including a load supporting structure and means for moving said structure through said opening, axle engaging means adjustably supported on said structure, remote means for controlling the operation of said lifting mechanism, a movable closure for said opening, means controlled by the movement of said lifting mechanism in either direction to open said closure during the initial movement of said mechanism and to close said closure during the final movement of said mechanism, and a signal controlled by said mechanism for informing an operator at said controlling means when said axle engaging means projects slightly above the floor.
